UNITED STATES PATENT OFFICE.

ISAAC E. EMERSON, OF BALTIMORE, MARYLAND.

KNOCKDOWN COUCH.

995,234.

Specification of Letters Patent. Patented June 13, 1911.

Application filed December 16, 1910. Serial No. 597,597.

To all whom it may concern:

Be it known that, ISAAC E. EMERSON, a citizen of the United States, and a resident of Baltimore, in the State of Maryland, have invented a new and Improved Knockdown Couch, of which the following is a full, clear, and exact description.

Among the principal objects which the present invention has in view are:—To provide portions of the adjacent chair structures which may be removed from their normal position to be fitted between the adjacent chairs, locking the same in fixed position and forming, in conjunction with the seats thereof, a bed mattress; to provide chairs with complementary auxiliary sections which may be removed from the normal position to form, in conjunction with other chairs and like complementary sections thereof, a reclining structure.

With these objects in view, the invention consists in forming chairs having elongated upholstered seat sections, and removable upholstered back sections, the combined length of two of said seat sections and one of said back sections being equal to the required length for a bed structure.

It consists further in constructing swivel chairs, such as employed in Pullman parlor cars, separated so that when turned toward each other, the total length from rear of back to rear of back is equal to the desired length of the bed structure.

It further consists in arranging the backs of seats of the character above mentioned to provide an upholstered back portion, being forwardly disposed to limit the seating portion of the seat to accommodate the sitting posture of the user.

It further consists in providing for chairs of the character described removable arm sections, which, when the said chairs are converted to use as a bed, may be stowed below the bed.

One embodiment of the present invention is illustrated in the accompanying drawings, wherein—

Figure 1 is a vertical longitudinal section, showing fixed swivel chairs of the character used in railway "chair cars", as converted to use as a bed; Fig. 2 is a horizontal section taken on the line 2—2 in Fig. 1, showing, in plan, the arrangement when the chairs are converted to the bed structure; Fig. 3 is a vertical section taken on the line 3—3 in Fig. 4, showing the chair as disposed for seat-

ing purposes; Fig. 4 is a horizontal section taken on the line 4—4 in Fig. 3, showing, in plan, the structural arrangement of the chair, when so used. A portion of the seat in this figure is cut away to show the bracket irons with which the chairs are provided for resting the edge of the back sections when employed to form a bed mattress; Fig. 5 is a vertical section taken on the line 5—5 in Fig. 6, showing the construction of one of the side arms of the chair; Fig. 6 is a detail view, in plan, of one of the side arms; and Fig. 7 is a detail view, in plan, of the removable back section of the chairs.

As shown in the accompanying drawings, the invention is applied to the class of chairs known as parlor chairs, as constructed and used in railway passenger cars. It will be understood, however, that chairs may be constructed in any suitable manner, swiveled or not, and stationary or portable. Under all conditions of usage, the structure remains practically the same, and the peculiarities of this structure consist substantially as shown in the present drawings.

The seat frame 12 is constructed in any approved and usual manner. As shown in the accompanying drawings, it is fixedly mounted upon a swivel head 13. The swivel head 13 is guidedly and rotatably mounted upon a pedestal 14, a friction-reducing bearing 15 formed of interposed devices being interposed between the head and pedestal. The frame 12 is usually constructed of a length greater than that provided for ordinary chairs. Fixedly or removably mounted on the frames 12 are cushions 16. The cushions 16 extend from the forward edge of the chair to the thin vertical back 17.

The back 17 is constructed from any suitable material. It is relatively thin and is preferably bowed to form the rounded back section, shown best in Fig. 2 of the drawings. The back and seat sections are framed rigidly in position by the corner posts 18, 18. The corner posts 18, 18 are connected at the top by the head frame 19. The frame 19 is angular in cross section, as shown best in Fig. 1 of the drawings, and the corner posts 18, 18 are each provided with an angular recess 20, as shown best in Fig. 2 of the drawings. Within the outer angle of the head frame 19 is permanently secured the head rest cushion 21. Within the inner angle of the recesses 20 are disposed the fixed side back cushions 22, 22.

Projected from the forward face of the corner posts 18 are socket brackets 23, provided to receive the dove-tailed tenons 24, 24. The tenons 24, 24 are formed at the ends of plates 25, 25 which are fixedly attached to the body 26 of each of the arms 27. The arms 27, 27 are provided with posts 28, the lower ends 29 whereof are adapted for insertion in the recesses formed in each of the sockets 30, 30. To limit the insertion of the end 29, the posts are each provided with a stop 31.

By reason of the construction just above described, the side arms of the complete chair may be inserted in operative position in a manner much resembling the attachment of the ordinary side rail of a bed frame, the tenons 24 entering the sockets 23 from above, and the ends 29 entering the recesses in the sockets 30. In this position the arms are rigidly held when the chair is employed as a seat, as best shown in Figs. 3 and 4 of the drawings. The sockets 30, 30 also serve to receive, in supporting relation, the lugs 32, 32, which are depended from the removable back cushions 33. The cushions 33, when thus united to opposite and adjacent chairs by the lugs 32, fitting within the sockets 30, are further supported by the sliding brackets 34, 34, which brackets are, as shown best in Fig. 4 of the drawings, disposed near the median line bisecting the front of the seat of the chair. In this manner both edges of the cushion section 33 are supported. The thickness of the sections 33, 33 is such that when the said sections are installed as shown in Figs. 1 and 2, the level of the upper surface of the assembled seat and back cushions is uniform.

40 The brackets 34, 34 are slidably mounted on the seat frames 12. Depended from the under side of each bracket is a handle portion 35. The handle portion 35 is extended through a slot opening 36 in the seat frame, whereby the forward and rearward extensions of the brackets are limited, permitting a projection beyond the seat frame, and a refraction inwardly beyond the forward edge thereof.

50 The back cushions 33, 33, when disposed as the back of the chair, are held in proper disposition by the rails 37, 37. The rails 37, 37 are inclined, substantially as shown in Fig. 3 of the drawings, thereby holding the cushions 33 between the seat cushion 16 and the lower side of the head frame 19, without further locking devices. When the cushions 33 are thus disposed, the lugs 32 pass between the rails 37 without interference with 60 the chair structure.

With a chair thus constructed and arranged, the operation, when the same is converted into a bed, is as follows: The arms 27, 27 are removed from adjacent chairs by 65 lifting the same vertically therefrom. The

arms are then disposed of in any suitable and convenient manner, preferably by placing same beneath the seat frames of the chair. The adjacent chairs are turned on the pedestals 14, so that their front edges are 70 oppositely disposed. The cushion sections 33, 33 are then lifted from their position in the back frame of the chairs and are mounted between the front edges of the chairs, the lugs 32, 32 of each cushion extending within the sockets 30, 30 of the opposite chairs, and the edge of the cushions 33, 33 are rested upon the brackets 34, 34, these being projected beyond the edges of the chairs by the operator, engaging for that 80 purpose the handles 35, 35. In this position of the cushions, the bed is arranged substantially as shown in Figs. 1 and 2 of the drawings, when it will be found that the distance between the back 17 of the one chair and the 85 back 17 of the other chair is equal to the length of the standard bed or Pullman bunk. With bed clothing provided, the couch or bed is now prepared for occupancy.

Chairs constructed substantially as above 90 described, portable or stationary, may be thus adapted for use in an ordinary Pullman car, as above set forth, or in steam boats, or in sample or other public rooms of hotels, thus providing for an emergency of over 95 crowding so frequent in vehicles or hostelleries of the kind mentioned.

It should be further mentioned in conjunction with this disclosure that in the ordinary Pullman cars the chairs of the character described will replace the usual fixed bench seats. In these cars the so-called upper berth will be retained and will be utilized to carry the thin mattress and bed clothing for the couch formed by the adjacent chairs. At 105 night the upper berth will be lowered as in the present employment, resting over or upon the tops of the chairs when arranged as a couch.

Having thus described my invention, what 110 I claim as new and desire to secure by Letters Patent is:—

1. A knock-down couch embodying a swivel chair, comprising a fixed back structure having a cushion pocket formed therein; an elongated seat frame; a cushion for said seat frame; a back cushion adapted to rest in and be held by said pocket in said back structure, said back cushion having a rigid supporting frame; socket brackets 115 mounted on said seat frame at the forward edge thereof; and holding lugs rigidly mounted on said back cushion frame adapted for insertion within said sockets to hold the cushion frame in position horizontally 120 extended from the front edge of said seat frame.

2. In a knock-down couch embodying a swivel chair having a rigid seat frame, a back structure comprising side posts rigidly 125

secured in vertical position upon said seat frame and arranged to form between said posts a longitudinally extended recess; a curved back frame for closing said recess; 5 a removable upholstered back cushion section adapted for disposal in said recess; and guide rails disposed in said recess to support said back cushion section.

3. In a knock-down couch embodying a 10 swivel chair having a rigid seat frame, a back structure comprising side posts rigidly secured in vertical position upon said seat frame and arranged to form between said posts a longitudinally extended recess, and 15 having at the exposed inner corner thereof protective cushions; a curved back frame for closing said recess; a removable upholstered back cushion section adapted for disposal in said recess; and guide rails disposed 20 in said recess to support said back cushion section.

4. In a knock-down couch embodying a swivel chair having a rigid seat frame, a 25 back structure comprising side posts rigidly secured in vertical position upon said seat frame and arranged to form between said posts a longitudinally extended recess, and having at the exposed inner corners thereof protective cushions; a curved back frame 30 for closing said recess; a removable upholstered back cushion section adapted for disposal in said recess; and a plurality of guide rails mounted in said recess to hold the said back cushion section within said recess and 35 in inclined position therein.

5. In a knock-down couch embodying a swivel chair having a rigid seat frame, a 40 back structure comprising side posts rigidly secured in vertical position upon said seat frame and arranged to form between said

posts a longitudinally extended recess; a head cushion section rigidly secured to and extended between said side posts to form a head cushion for said seat; a curved back frame for closing said recess; a removable 45 upholstered back cushion section adapted for disposal in said recess; and guide rails disposed in said recess to support said back cushion section.

6. A knock-down couch, comprising a 50 plurality of permanently stationed swivel chairs each having elongated upholstered seat frames; a removable upholstered back frame section for each chair, said sections being equal to one-half the space between 55 the front edges of said chairs when same are faced toward each other; and fastening means provided on said chairs for holding the said back sections in locked position between said chairs. 60

7. A knock-down couch, comprising a plurality of permanently stationed swivel chairs each having elongated upholstered seat frames; a removable upholstered back frame section for each chair, said sections 65 being equal to one-half the space between the front edges of said chairs when same are faced toward each other; and fastening means provided on said chairs for holding the said back sections in locked position 70 between said chairs, said chairs being provided with removable side arm structures.

In testimony whereof I have signed my name to this specification in the presence of two subscribing witnesses.
